Primary Examiner — Deanna L Pratt(74) *Attorney, Agent, or Firm* — Birch, Stewart, Kolasch & Birch, LLP(57) **CLAIM**

The ornamental design for a smart key for vehicles, as shown and described.

DESCRIPTION

1. Smart key for vehicles

1.1 : Perspective

1.2 : Front

1.3 : Back

1.4 : Left

1.5 : Right

1.6 : Top

1.7 : Bottom

1.8 : Reference

The claimed design is an artificial intelligence smart key for vehicles that is connected to docking stations in a vehicle or at home, and displays home or vehicles information on the top display; reproduction 1.8 is a reference view showing a state of use in which a smart key is connected to a docking station; the broken lines showing the docking station in reproduction 1.8 form no part of the claimed design.
